UNITED STATES PATENT OFFICE.

JACOB ALTMAN, OF LOS ANGELES, CALIFORNIA, ASSIGNOR TO J. W. SCHULTZ, OF LOS ANGELES, CALIFORNIA.

DESIGN FOR GROUP STATUETTE.

Application filed April 17, 1923. Serial No. 5,842. Term of patent 14 years.

To all whom it may concern:

Be it known that I, JACOB ALTMAN, a citizen of the United States, residing at Los Angeles, in the county of Los Angeles and State of California, have invented a new, original, and ornamental Design for Group Statuettes, of which the following is a specification, reference being had to the accompanying drawing, forming part thereof.

The figure is a view of a group statuette, showing my new design.

I claim:

The ornamental design for a group statuette, as shown.

JACOB ALTMAN.
